UNITED STATES PATENT OFFICE

EDWIN S. ROSCOE, OF ROCHESTER, NEW YORK, ASSIGNOR TO YAWMAN & ERBE MFG. CO.,
OF ROCHESTER, NEW YORK, A CORPORATION OF NEW YORK

FLUSH TYPE GUIDE ROD

Application filed March 17, 1932. Serial No. 599,412.

This invention relates to filing devices and more particularly to guide rods or retaining rods for use in such devices.

In various types of filing receptacles, it is customary to provide a retaining rod commonly known as a guide rod for retaining cards and guides or the like, against removal while the rod is in position. It is customary at the present time to provide a knob at one end of the rod, which knob protrudes through the front of the receptacle so that it is easily grasped when it is desired to withdraw the rod from the receptacle. This knob is usually threaded into the front of the drawer and it must be unscrewed to remove the knob and rod. The knobs of such guide rods are monotonously similar in appearance, they are often too conspicuous, they present obstructions to catch clothing and dust cloths, and they are frequently not in harmony with the flush finished surfaces of high grade, surrounding furniture.

The advantages of flush guide rod ends has been previously recognized, but in the past the guide rods have been retained in position by a lock having its key slot accessible through the front end of the guide rod so that in addition to requiring a key for releasing the guide rod, its front end was rendered conspicuous by the presence of the key slot.

Another device resorted to in order to obtain a flush guide rod, has been the use of a detachable knob or sleeve which slips over the front end of the guide rod to release a retaining spring, acting similarly in its effect to the aforementioned key. This device requires a conspicuous annular space between the guide rod and the opening in the receptacle front, to allow space for operation of the knob or sleeve.

All of the foregoing arrangements have failed to provide a guide rod having its front end substantially flush with the front of the receptacle, with no appreciable annular space between the rod and the receptacle front, with the end of the rod unmarred by a key slot or other releasing means, and without the disadvantage of an extra part like a key which may become mislaid during the inter-

val between the usually infrequent use of the guide rod.

In accordance with the present invention, there is provided a guide rod arrangement in which the front end of the rod is flush with the front face of the receptacle and in which the front end of the rod is an unbroken plane surface that may have the same finish as the front of the receptacle, so that the only break in this portion of the receptacle is the inconspicuous line due to the clearance between the front end of the rod and the receptacle front.

Another feature of the invention relates to a guide rod having its front end flush with the front of the receptacle and with releasing means for the guide rod accessible at a point adjacent to one of the inside edges of said receptacle front.

A further feature of the invention relates to a flush type guide rod provided with ejecting means mounted between the principal planes of the drawer front and its detachable liner or at some other convenient location like the back end of the drawer, and a retaining latch mounted between the principal planes of the front and its liner in such a manner that the liner, the ejecting spring for the guide rod and the releasing latch for the rod, may be readily inserted after assembling and finishing the principal parts of the receptacle, and may also be readily removed from the receptacle if they should subsequently require replacement.

These and other features of the invention will appear from the detailed description and claims when taken with the drawings, in which Fig. 1 is a perspective view of a filing cabinet; Fig. 2 is a side elevation partially sectionalized on the line 2-2 of Fig. 1; Fig. 3 is a horizontal section taken on the line 3-3 of Fig. 1 showing the relation between the drawer front, its liner, and the drawer bottom, as well as the mounting of the front end of the guide rod, together with the ejector and the latch therefor; Fig. 4 is a vertical sectional view of a portion of a drawer taken on the line 4-4 of Fig. 3; Fig. 5 is a detailed sectional view taken on the line 5-5 of Fig. 4; Fig. 6 is a perspective view of a guide rod with a modified form of ejecting means and

latch; Fig. 7 is a vertical sectional view of a fragment of the drawer showing the mounting of this modified form of the invention; Fig. 8 is a vertical sectional view on the line 5 8—8 of Fig. 7; and Figs. 9 and 10 represent vertical sectional views taken at right-angles to each other, of a further modified form of the invention.

The preferred form of the invention is illustrated in Figs. 1 to 5 where it is represented as incorporated in a filing cabinet 5 having three compartments for the reception of the drawers generally designated 6. Each drawer includes a drawer front 7 formed of sheet-material having integral side flanges (not shown) and provided at its top edge with an integral, horizontal flange 8, which in turn is formed with a down-turned extension 9 extending generally in a direction parallel to the drawer front. The lower edge of the drawer front is likewise provided with a horizontal flange 10 formed with an upstanding extension 11 which is likewise generally parallel to the front of the drawer. The drawer 20 also includes a rear end portion (not shown), sides 13 which may be attached to the integral side flanges (not shown) on the drawer front 7 in any well-known manner, and a bottom 14 having a channel portion depressed below the plane thereof to receive a guide rod 28 and defined by the inclined sides 15, 16 and the horizontal portion 17 (Fig. 4). The drawer bottom is provided at its front end, on each side of the mentioned channel portion, with the downturned angular flanges 18, which engage the extension 11 (Fig. 5) on the face thereof adjacent the drawer front. The drawer front is reinforced by a liner 19 provided at its top with a curved portion 20, which engages the portions 8 and 9 of the upper part of the drawer front as shown in Fig. 2. The lower edge of the liner is formed with an extension 19a, projecting into the channel in the drawer bottom, and with rectangular forwardly bent extensions 21 (Figs. 4 and 5) resting in part on the bottom 14 of the drawer at each side of said channel, and having their front edges preferably in engagement with the inner surface of the drawer front 7. The space 22 between extensions 21 of the liner adjacent the guide rod latch mechanism to be referred to, accommodates the several parts thereof. It will be understood that the liner may be held in the position shown by any one of several well-known means, such as by the bolts of the drawer pull 23 passing therethrough and through the registering openings in the drawer front, and the spacers 24, in which position the several parts are normally held by the nuts (not shown) but engaging the threaded bolt ends in depressions 25 in the liner. The drawer front 7 is provided with a guide rod opening 26 of a size just sufficient to receive with proper clearance the front end 27 of the guide

rod 28 normally positioned in the channel of the drawer bottom. This guide rod at its front end is formed with a cylindrical portion 29, an annular latch-receiving groove 31, and a second cylindrical portion 30 having a 70 smaller diameter than 29. The cylindrical portion 30 at its rear side tapers to the diameter of the guide rod proper 28, so that the latching portion thereof can be easily inserted in the opening 26. It will be understood 75 however, that the exact shape of the portion 30 is not an essential feature of the device, since it may be tapered to have the contour of a truncated cone rather than that of a combined cylinder and cone as shown. 80

In the space between the drawer front 7 and the liner 19, the latching and ejecting means for the guide rod is mounted. This ejecting means includes a flat spring 32 having the outline shown in Fig. 4 and provided with an opening 33 through which the guide rod is inserted, the vertical diameter of 33 being smaller than the diameter of 29 and larger than the diameter of 30. As shown in Figs. 3 and 4 this spring is supported at one end by the lug 34 struck up from the angular portion 18 on the drawer bottom, which lug engages the elongated opening 35 in the spring. The other end of the ejector spring is supported on the angular 85 extension 37 of a spring latch 38 which passes through registering openings in members 11 and 18, and the circular opening 36 in the ejector spring. This spring latch, the shape of which can best be seen in Figs. 3 and 4, 90 passes through cut-out portions 39 and 40 in the inclined sides 15 and 16 of the channeled portion of the drawer bottom. When the spring latch is released after removal of the guide rod 28 it is desirable for it to spring 95 down against either the lug 41 (see Figs. 4 and 5) struck out of extension 11 in drawer front, or against the bottom of the slot 39, thus holding it up far enough for easy insertion of the guide rod under it. When the guide rod is inserted further, the tapered portion of 30 presses the spring latch upward, in which case it is restrained at 37 and at the top of the slot 40; while it is free to move vertically in the slot 39. The handle 100 portion 42 of the spring latch 38 extends along the lower surface of the drawer bottom 14 in spaced relation thereto, and rests against the rear face of the extension 11 (Fig. 3) where it is out of the way and yet is easily accessible 105 as soon as the drawer is partially opened. Thus when it is desired to remove the guide rod from the drawer front it is merely necessary to open the drawer partially so that the handle 42 of the spring latch is accessible 110 at the lower edge of the drawer front and this handle is then raised so that the spring latch 38 disengages the front face of the cylindrical portion 30 of the guide rod. As soon as the guide rod is thus unlatched, the 115

ejector spring 32, in engagement with the rear face of the cylindrical portion 29 of the guide rod, moves to the position indicated by the dot and dash lines in Fig. 3, thereby 5 moving with it the guide rod 28 to the position where its front end 27 is protruding as indicated in dot and dash lines in this figure.

When assembling or dismantling the 10 ejector and spring latch, the liner is removed leaving the locations for the ejector and latch fully exposed. In assembly, the spring latch is inserted from under the drawer bottom slots 39 and 40; then it is turned so that the angular extension 37 registers with and slips 15 into the corresponding openings in 11 and 18. The ejector spring 32 is then inserted so that one hole 36 slips over the angular extension 37 of the spring latch and the slot 35 slips over lug 34. A reversal of these operations 20 disassembles the parts.

In Figs. 6, 7 and 8, there is also indicated, 25 a modified form of the invention wherein a latch, accessible from the inner edge of the drawer front, may be moved substantially horizontally to the right into its unlatching position as shown in Fig. 6, or to the left so that the latch engages the guide rod as shown in Fig. 8. The structure of the drawer in which the guide rod with this modified form 30 of ejecting and latching means is used, has been very much abbreviated since this form of the invention may be used with almost any type of drawer and especially the type of drawer illustrated in the foregoing figures. 35 In this arrangement also, the drawer front 7 has a guide rod opening 26 to receive the guide rod 28, the front end of which is likewise provided with cylindrical portions 29 and 30 slightly spaced from each other to form a 40 notch 31 for receiving the latch portion 45 of the latch mechanism generally designated 46. On the liner 19 there is mounted in any suitable manner an ejector spring 47, the lower end of which is shown as apertured to 45 receive the guide rod 28 and to engage the rear face of the cylindrical portion 30 thereof. The latch mechanism 46 includes two handles 48 and 49 which are accessible from the rear of the lower edge of the drawer 50 front so that the latch 46 may be moved in openings 50 in the sides 15 and 16 of the drawer bottom channel to the left to engage the front face of the cylindrical portion 30 of the guide rod and thus hold the guide rod 55 in its closed position with its front end 27 flush with the drawer front, as shown in Fig. 7, and to the right to release the rod.

In the modified form of the invention shown in Figs. 9 and 10, the drawer structure is also very much abbreviated since it 60 may be similar to any one of many well-known types, especially the type shown in Figs. 1 to 5. In this arrangement the latch 57 is in the form of a flat strip provided with 65 a key hole opening 60. This latch has a han-

dle 59 by which it may be moved up and down in the guides provided on the liner 19, being limited in its downward movement by the stop 58, when the guide rod 28 is removed. This guide rod in this instance, is also provided with cylindrical portions 29 and 30 arranged to form a latch receiving notch so positioned that it will be engaged by the restricted portion of the key hole opening 60 when the front end of the guide rod is flush 70 with the exposed surface of the drawer front 7. The ejecting spring 61 for the guide rod may be supported in various ways, but it is herein represented as mounted on the rear end of the drawer.

It will be understood that the present disclosure is merely typical of a few of the many possible forms of the invention which is not to be limited thereby except as specifically defined in the appended claims.

What I claim is:

1. In a receptacle for the storage of records, a receptacle front having an opening therein, a guide rod insertable through said opening, and means accessible only at an edge of said receptacle front for retaining said guide rod against movement through said opening, and for releasing said guide rod for such movement.

2. In a receptacle for the storage of records, a receptacle front having an opening therein, a guide rod insertable through said opening with one of its ends substantially flush with the receptacle front and in engagement with the wall of said opening, and means only accessible immediately at the rear of said receptacle front for releasing and ejecting said guide rod through said opening.

3. In a receptacle for the storage of records, a receptacle front having an opening therein, a liner mounted in spaced relation to said front, a guide rod insertable through said opening with one end thereof substantially flush with the receptacle front, an ejecting device tending to eject said guide rod through said opening, and a latching device normally holding said guide rod with one of its ends flush with the front of said drawer, said devices being mounted between the principal planes of said receptacle front and said liner and said latching device being accessible adjacent one edge of said front.

4. In a receptacle for the storage of records, a receptacle front, having an opening therein, a guide rod having its end portion shaped to substantially fill said opening and with its end flush with said front, an ejecting spring normally tending to eject said guide rod through said opening, a latch normally holding said guide rod with its end substantially flush with the face of said receptacle front against the action of said ejecting spring, and means accessible only adjacent the

rear of said front for disengaging said latch whereby said spring ejects said rod.

5. In a receptacle for the storage of records, a front member having an opening therein, a lining member having a cut-out portion in registry with said opening, said lining member being mounted in spaced relation to the front member to form a chamber, a guide rod having one end normally flush with the face of said front member and of a size sufficient to substantially close said opening, ejecting means for said guide rod mounted between the principal planes of said members, and latching means for retaining said guide rod in position flush with the exposed surface of said front against the action of said ejecting means, said latching means being operable from the edge of said front in the space between the principal planes of said front and lining members.

6. In a receptacle for the storage of records, a front member having an opening therein, a lining member having a cut-out portion in registry with said opening, said lining member being mounted in spaced relation to said front member to form a chamber, a guide rod having one end normally flush with the face of said front member and of a size sufficient to substantially close said opening, an ejecting member for said rod mounted between the principal planes of said member, and latching means for retaining said rod in flush relation with the exposed face of said front member, said latching means being mounted between the principal planes of said members and being accessible from the edge of said front member.

7. In a receptacle for the storage of records, a front member having an opening therein and provided at its lower edge with an upstanding extension, a bottom member for said receptacle having a downwardly extending flange supported adjacent said extension, a guide rod insertable into said opening and substantially flush with the exposed surface of said front, said guide rod being provided with a catch, a latch supported on said receptacle near the lower edge thereof to engage said catch, an ejector spring normally engaging a portion of said guide rod, said ejector being supported in part by said latch.

8. In a receptacle for the storage of records, a receptacle front having an opening therein and provided with a spaced upstanding extension, a bottom member for said receptacle provided with a downwardly extending flange engaging said extension, a liner supported in spaced relation from said front member, a guide rod inserted in said opening, a latch engaging a portion of said guide rod to hold it in its normal position and provided with an angular portion, and an ejector spring tending to eject said guide

rod through said opening, said ejector spring being supported at one end adjacent said flange and supported at its other end on the angular extension of said latch, said latch and ejector being mounted and said latch being operable between the principal planes of said front member and said liner.

9. In a receptacle for the storage of records, a receptacle front having an opening therein, a liner mounted in spaced relation to said receptacle front, a guide rod insertable through said opening and having one end normally flush with the exposed face of said front member, said guide rod being provided with latching means, an ejector spring tending to eject said guide rod through said opening, and a latch member movable in a plane parallel to said front between the principal planes of said front and said liner to engage and disengage the latching means on said guide rod.

10. In a receptacle for the storage of records, a receptacle front having an opening therein, a liner mounted in spaced relation to said receptacle front, a guide rod insertable through said opening and having one end normally flush with the exposed face of said front member, said guide rod being provided with latching means, an ejector spring tending to eject said guide rod through said opening, and a latch member movable horizontally between the principal planes of said front and said liner to engage and disengage the latching means on said guide rod.

11. In a receptacle for the storage of records, a receptacle front having an opening therein, a guide rod insertable through said opening, and vertically movable means accessible only at an edge of said receptacle front for retaining said guide rod against movement through said opening and for releasing said guide rod for such movement.

12. In a receptacle for the storage of records, a receptacle front having an opening therein, a guide rod insertable through said opening, and horizontally movable means accessible only at an edge of said receptacle front for retaining said guide rod against movement through said opening and for releasing said guide rod for such movement.

13. In a receptacle for the storage of records, a receptacle front having an opening therein, a liner mounted in spaced relation to said receptacle front, a guide rod insertable through said opening and having an imperforated end normally closing said opening, said guide rod being provided with latching means, an ejector spring tending to eject said guide rod through said opening, and a latch member movable between the principal planes of said front and said liner to engage and disengage the latching means on said guide rod.

EDWIN S. ROSCOE.
